SAMUEL P. HARTMAN, OF KANSAS CITY, MISSOURI.

CAN HOLDING AND OPENING DEVICE.

1,252,108.

Specification of Letters Patent. Patented Jan. 1, 1918.

Application filed July 7, 1917. Serial No. 179,242.

To all whom it may concern:

Be it known that I, SAMUEL P. HARTMAN, a citizen of the United States, residing at Kansas City, in the county of Jackson and 5 State of Missouri, have invented a new and useful Can Holding and Opening Device, of which the following is a specification.

My invention relates to can holding and opening devices, and the objects of my invention are, first, to provide a cheap, durable and efficient holding and opening device for 10 hermetically sealed cans and jars, second, to provide clamping jaws with can supporting flanges to receive and hold cans of different sizes during the opening process, third, to provide an adjustable opening device and, 15 fourth, to provide the opening device with a two-edged blade adapted to cut forwardly and backwardly, and slidably mounted on 20 the opening device.

I attain these objects by means of the mechanism illustrated in the accompanying drawing, in which—

Figure 1, is a side elevation of the device 25 in operative position; Fig. 2, is a top plan view of the device; Fig. 3, is a side elevation of the opening device and showing the two-edged blade; Fig. 4, is a top plan view of the device and showing the opening device operative in cutting the top of a can, 30 and, Fig. 5, is a rear elevation of the device and showing the slideway and slide member in the supporting leg to vertically adjust the opening device.

Similar numerals of reference refer to corresponding parts throughout the several views.

The numeral 1, indicates a table fragment. 2, is an attaching device, which is provided 40 with a U-shaped yoke 3, having a press-screw 4, mounted in its lower limb, and which is adapted to press upwardly against the lower side of the table top to hold the device hereinafter described, in place. A 45 bracket 5, is formed integral with the upper limb of the yoke 3, and a hole 6, is apertured horizontally therein, and the hole provided with internal screw threads, the horizontally 50 disposed shelf 7, of the bracket being disposed and adapted to receive and rigidly support a jaw 8, provided with an elliptically-shaped inwardly projecting horizontally disposed supporting flange 9, on its lower edge, the terminal portions of said 55 flange being depressed to lie in a plane lower

than the flange proper, to form supporting arms 10 and 11. A jaw 12, having vertically extending sides, similar to the sides of the jaw 8, but extending in the form of a circle, is provided with an inwardly projecting horizontally disposed supporting flange 13, which is fixed on its lower edge and adapted to register with the flange 9, and to bear upon the upper sides of the supporting arms 10 and 11, and slide thereon. A 60 standard 14, is attached to the rearward side of the jaw 12, and is extended downwardly to the table top, its lower end being turned inwardly and upwardly to form a foot 15, which is adapted to slide on the table with 65 a minimum of friction. A hole 16, is apertured in the standard in such a manner that it will register with the hole 6, in the bracket. A rod 17, provided with screw-threads on its outer end, is entered in the holes 6, and 16, 70 the screw end of the rod being engaged by the internal screw threads in the hole 6. Collars 18, are mounted on the rod at opposite sides of the standard and are adapted to hold the rod attached to the standard and 75 movable therein. A crank 19, is mounted on the outer end of the rod to turn the latter. A slideway 20, is formed longitudinally in the standard 14, in which slideway a slide member 21, is slidably mounted. An inwardly 80 extending arm 22, is hingedly mounted on the upper end of the slide member 21, and is provided with a longitudinally extending slotted aperture 23, in which slot a puncturing center punch 24, is slidably mounted, the 85 upper end of the punch being provided with an anvil 25, which is adapted to receive pressure to force the punch to puncture the top of a can disposed therebelow. An arm 26, is pivotally mounted on the upper end of the 90 punch, between the anvil and the upper side of the arm 22, and is provided with a longitudinally extending slotted aperture 27, in which slot, a blade 28, is slidably mounted. The blade 28, is provided below the arm 26, 95 with oppositely disposed cutting edges 29 and 30, and with a handle 31, attached to its upper end, above the arm.

The device constructed as I have above described provides convenient and ever-ready means for simultaneously holding and opening a sealed can, and which is operated as follows: The jaws are separated by turning the crank 19, to the left, which action 105 presses the jaw 12, outwardly from the jaw 110

8, the former jaw sliding on the supporting arms 10 and 11, the standard 14, sliding in the same direction on the table top. A sealed can 32, is lodged on the flanges 9 and 13, and 5 the jaws forced to clamp the can by turning the crank 19, to the right. The arms 22 and 26, are swung over and upon the top of the can, the slide member being raised to admit of this action. The punch 24, is moved in 10 the slot 23, in the arm 22, to the approximate center of the can top, when a suitable pressure is applied to the anvil 25, to force the punch through the can top. The blade 28, is then moved in the slot 27, in the arm 15 26, to the point at which the can top is to be cut, and either a pushing or a pulling pressure applied to the blade, will serve to cut the can top in circular direction to open the can, as shown in Fig. 4. When the can is 20 opened, the arms 22 and 26, are swung outwardly, and the slide member depressed, when the jaws may be separated to release the can. The elliptically shaped rigid jaw 8, combined with the circular-shaped jaw 12, 25 provides efficient means to clamp in the device cans of different diameters, ranging

from the maximum capacity of the jaw 12 to and below the same.

Having described my invention what I claim is—

30 In a can clamping device, the combination of a fixed member having a vertical back portion extending in the form of an ellipse and provided at its lower edge with an inwardly projecting flange provided with projecting arms fixed on its terminal portions, a movable member having a vertical back portion extending in the form of a circle provided at its lower edge with an inwardly projecting flange adapted to lie in the plane 40 of the flange on said fixed member, the terminal portions of the flange being slidably engaged by the arms on said first mentioned flange, and means connected between said members and adapted to adjust the movable 45 member to the fixed member.

Kansas City, Missouri, July 5, 1917.

SAMUEL P. HARTMAN.
